UNITED STATES PATENT OFFICE

143,449

DESIGN FOR A TOY AIRPLANE ENGINE

Bertram H. Stewart, New York, N. Y., assignor to
Streamline Motor Corp., New York, N. Y., a
corporation of New York

Application August 8, 1945, Serial No. 121,311

Term of patent 14 years

(CL. D71—1)

To all whom it may concern:

Be it known that I, Bertram H. Stewart, a citizen of the United States, residing at New York city, in the county of New York and State of New York, have invented a new, original, and ornamental Design for a Toy Airplane Engine, of which the following is a specification, reference being had to the accompanying drawing, forming part thereof.

In the drawing

Fig. 1 is a side elevational view of a toy airplane engine showing my new design;

Fig. 2 is a top plan view thereof, and

Fig. 3 is a front elevational view.

I claim:

The ornamental design for a toy airplane engine, substantially as shown.

BERTRAM H. STEWART.
